Primary Examiner — Cathron C Brooks*Assistant Examiner* — Kevin Rudzinski(74) *Attorney, Agent, or Firm* — Renner, Otto, Boisselle & Sklar, LLP(57) **CLAIM**

The ornamental design for a light conductive light emitter for a light emitting diode light source, as shown and described.

DESCRIPTION

FIG. 1 is a perspective view of a light conductive light emitter for a light emitting diode light source showing our new design.

FIG. 2 is a front view thereof.

FIG. 3 is a back view thereof.

FIG. 4 is a side view from the right side thereof.

FIG. 5 is a side view from the left side thereof; and,

FIG. 6 is a bottom view thereof.

The broken lines shown in the drawing disclosure illustrate unclaimed environmental structures that form no part of the claimed design.
